UNITED STATES PATENT OFFICE.

HENRY B. SARGENT, OF NEW HAVEN, CONNECTICUT, ASSIGNOR TO SARGENT & COMPANY, OF NEW HAVEN, CONNECTICUT, A CORPORATION OF CONNECTICUT.

DESIGN FOR AN OPERATING-BAR FOR EMERGENCY-EXIT LOCKS.

49,410.

Specification for Design.

Patented July 18, 1916.

Application filed January 28, 1916. Serial No. 74,864. Term of patent 14 years.

To all whom it may concern:

Be it known that I, HENRY B. SARGENT, a citizen of the United States, residing in the city and county of New Haven and State of Connecticut, have invented a new, original, and ornamental Design for an Operating-Bar for Emergency-Exit Locks, of which the following is a specification, when taken in connection with the accompanying drawing.

In the drawing, Figure 1 is a front eleva-

tion of an operating bar for emergency exit locks embodying my design; Fig. 2 is an edge view of the bar; Fig. 3 is an end view of the bar; and Fig. 4 is a section on line 4—4 of Fig. 1.

What I claim is:—

The ornamental design for an operating bar for emergency exit locks, substantially as shown.

HENRY B. SARGENT.
